HANDLE FOR GARDEN TOOLS OR THE LIKE

Kyoichi Nagaoka, 9, Dainikawashimaso, 5-343-1 Hikari-machi, Kokubunji-shi, Tokyo-to, Ashikaga, Japan

Filed Jan. 22, 1968, Ser. No. 10,237

Term of patent 7 years

Int. Cl. D8—01, 02

U.S. Cl. D35—2

FIG.3

FIG.2

FIG. 6

FIG. 4

FIG. 5

FIG. 1 is a front elevation view of the handle for garden tools or the like showing the new design;

FIG. 2 is a side elevation view thereof;

FIG. 3 is an end view thereof;

FIG. 4 is a front elevation view of a modification of the handle for a tool;

FIG. 5 is a side elevation view thereof; and

FIG. 6 is an end view thereof.

The broken line showing of tool elements is for illustrative purposes only. The sides not shown are identical to the sides shown, and the end opposite to that shown is a plain circle.

I claim:

The ornamental design for a handle for garden tools or the like, substantially as shown and described.
